UNITED STATES PATENT OFFICE.

WILLIAM S. FISKE, OF STAMFORD, CONNECTICUT.

STEAM-ENGINE.

SPECIFICATION forming part of Letters Patent No. 231,551, dated August 24, 1880.

Application filed January 12, 1880.

To all whom it may concern:

Be it known that I, WILLIAM S. FISKE, of Stamford, in the county of Fairfield and State of Connecticut, have invented a new and valuable Improvement in Steam-Engines; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side view, partly in section, of my improved steam-engine. Fig. 2 is a front view with the front of the steam-chest removed.

This invention has relation to steam-engines having oscillating cylinders; and it consists in the construction and novel arrangement of parts, as hereinafter shown, described, and set forth in the claims.

In the accompanying drawings, the letter A designates the frame-work of this engine, having the bearings *a* for the cylinder-journals *b*, which are bored to receive the steam-supply pipe *c* and the exhaust-pipe *d*, respectively, as shown in the drawings.

B represents the oscillating cylinder, around the waist of which are the steam-passages *e*, leading from the steam-supply to the steam-chest C, which is circular in form, and constructed on the side of the cylinder, between its body and the journal on this side. The wall of this valve-chest next the cylinder forms the seat *g* of the slide-valve D, which is of circular form and composed of two sections or parts, *h*, of annular form, arranged one within the other, in order to expand under the pressure of the steam, and thereby preserve tight joints in the seat *g* and the seat *k*.

As the axis of the slide-valve is in the vertical plane, by the arrangement referred to a balanced valve results, the pressure on the opposite seats being equalized, and without reference to the weight of the rings constituting the slide-valve.

In the seat *g* are the steam-ports *l l*, through which the steam passes from the valve-chest to the cylinder. The exhaust-steam escapes through these same ports *l l* into the opening or hollow center of the slide-valve, whence it passes into the air through the pipe *d*. This

pipe is inserted into the plate E, which forms the exterior wall of the valve-chest, and by its interior surface the valve-seat *k*. This plate carries one of the cylinder-journals, as shown. 55

Stuffing-boxes are placed in the journals around the steam and exhaust pipes, as shown at *m m*.

The valve-stem *n* extends through a slide-way, *a'*, in the valve-chest, and is rigidly connected at its outer end to a link, *p*, which is transversely arranged, and is provided with an arc-shaped slot, *q*, the curvature of which is from the center of oscillation of the cylinder, or nearly so. To this link *p* is attached a lug 60 or stud, *r*, which reciprocates in a slotted guide, F, which is connected to the cylinder, the slot of said guide being in the plane of the valve-stem and of the axis of the cylinder. It is apparent that this guide F oscillates with 65 the cylinder.

G represents the eccentric, which is turned by the piston-rod H, and serves to reciprocate the pitman K in a uniform and steady manner, the head of said pitman being connected 75 to the frame by the engagement of its stud or pin *t* with the vertically-slotted guide L, which is rigidly connected to said frame below the journal-seat of this side. The head of this pitman also engages the curved link *p* by 80 means of a stud or pin, *t'*, and thereby serves, when operated by the eccentric and guided by the fixed slotted plate L, to move the valve-stem in an even and regular manner, said valve-stem being kept true by the oscillating 85 guide F on the cylinder.

I am aware that the patent of King, No. 48,563, of 1865, shows a valve-stem pivoted in the slot of an arc which is rigidly connected to a vertical slide, to which the pitman from 90 the eccentric is pivoted, and I do not claim such device.

Having described this invention, what I claim, and desire to secure by Letters Patent, is—

1. The oscillating cylinder B, having the waste-passages *e*, the steam-chest C, the vertical annular slide-valve D, its center opening, the vertical valve-seats *g* and *k*, the ports *l l*, and the escape-pipe *d*, all constructed and arranged to operate substantially as shown and described. 95 100

2. In an oscillating steam-engine, the valve-stem *n*, carrying the rigidly-attached slotted link *p*, the eccentric pitman *K*, pivoted in the slot of the valve-stem link and in the vertical frame-guide *L*, and the slotted cylinder-guide *F*, engaging the pivot-stud of the valve-stem link, as specified.

In testimony that I claim the above I have hereunto subscribed my name in the presence of two witnesses.

WILLIAM SHERWOOD FISKE.
